UNITED STATES PATENT OFFICE.

MILTON T. ROSENHEIM, OF PHILADELPHIA, PENNSYLVANIA.

LUMINOUS SWITCH-KEY.

1,147,269.

Specification of Letters Patent. Patented July 20, 1915.

Application filed June 16, 1914. Serial No. 845,377.

To all whom it may concern:

Be it known that I, MILTON T. ROSENHEIM, a citizen of the United States, and a resident of the city of Philadelphia, county 5 of Philadelphia, and State of Pennsylvania, have invented certain new and useful Improvements in Luminous Switch-Keys, of which the following is a specification, reference being had to the accompanying draw- 10 ing.

The principal objects of my invention are to provide a luminous switch key for use in turning on or off electric switches or controlling cocks of gas fixtures or the like, or 15 for use in push buttons, push switches or pendant switches of such construction that the key, push or pendant as the case may be shall be visible in a dark room from any position; to provide a luminous switch key, 20 push, pendant or the like which shall permanently retain its luminosity under all conditions; which shall not require exposure to daylight or artificial light from time to time, in order to maintain it in a luminous condi- 25 tion, and to provide a luminous switch key, push, pendant or the like which may be cheaply and easily constructed and which may be used in connection with the ordinary type of gas or electric switches or fixtures 30 now upon the market.

My invention further includes all of the other various novel objects and features hereinafter more definitely specified and described.

35 In the drawing forming a part of this specification, Figure 1 is a side elevation of a luminous switch key embodying one form of my invention; Fig. 2 is an end view thereof, and Fig. 3 a transverse section taken 40 upon the line 3—3 of Fig. 1. In Fig. 4 is shown a side elevation partially in section of a slightly modified form of key; Figs. 5 and 6 being respectively an end view of such a key and a transverse section thereof on the 45 line 6—6 looking in the direction of the arrows. In Figs. 7 and 8 is shown a further slightly modified form of key, Fig. 8 being a vertical central section of the key and Fig. 7 an end view thereof partially in section, 50 such section being taken on the line 7—7 in Fig. 8, looking in the direction of the arrows. Figs. 9 and 10 show respectively still other slightly modified forms of switch keys embodying my invention, each of said figures 55 depicting such keys in substantially central vertical section. In Figs. 11 and 12 are re-

spectively shown elevational views, partially in central vertical section, of pendants embodying the features of my invention, and in Figs. 13 and 14 are shown similar views 60 of two forms of push buttons also embodying the features of my invention.

Referring now to the drawings, one embodiment of my invention shown therein in Figs. 1, 2 and 3 may consist of a key having 65 a body portion 1 which may be constructed integrally or by cementing or otherwise fastening together two or more sections or members 2, 3 by means of a suitable adhesive 5, or in any other desired manner, one or more 70 of the sections being preferably formed of any desired transparent or translucent material, such as glass or celluloid. The sections 2 and 3, if the key be formed in sections and not integral, may be of any desired 75 shape and are preferably so formed as to provide a cavity 6 of any desired depth in the interior of the key when the said sections are in assembled position, the dimensions of the cavity being limited merely by the limits 80 afforded by the key, within which the cavity may be formed of any desired size. If desired, however, the body of the key, instead of being formed in sections, may be formed integrally, either by blowing, molding or 85 otherwise.

For the purpose of attaching the key to the switch or other object, any suitable means may be provided, and for this purpose the body of the key, as shown in Figs. 90 1, 2 and 3 may be provided, at one end, preferably somewhat enlarged for the purpose, with a suitable threaded projection or shaft 8, preferably threaded or otherwise suitably retained within a suitable aperture 95 in the body of the key, or else the shaft may be permanently attached to the switch, and means, consisting of a suitable threaded aperture 10, or the like, provided upon the key for the purpose of receiving the end of 100 the shaft, as shown in Fig. 4, or other equivalent means employed.

Within the cavity 6 and preferably before the two sections of the key are cemented or otherwise secured together, if the same be 105 not formed integrally, is introduced a luminous substance 12, in any desired quantity, which substance may preferably consist of radiumized zinc sulfid, or some other radiumized substance or compound. This substance may be placed within the cavity in solid, liquid, pasty or powdered form, or

it may preferably, in this form of the invention, be applied as a coating to the walls of the cavity, as a coating 12, in any desired manner. In case the body of the key be formed integrally instead of in sections, it will be necessary to provide a suitable opening into the cavity for the purpose of introducing the luminous substance, which may, after the coating has been applied, be closed in any desired manner. It will be evident that as the cavity is of appreciable extent in every direction, the coating upon its walls will be visible from any point from which it may be viewed when the key is in position upon a switch, as from no point from which it may be observed when in position, will it present merely a hair-like line to the eye of the observer.

In Figs. 4, 5 and 6 is shown a slightly modified form of switch key in which the body of the key may be formed in two or more sections 15 and 16, suitably secured together, as by an adhesive 5 and provided with means consisting of a suitable threaded aperture 10 or the like for the attachment of the key to the stub shaft of the switch, the section 15 being preferably of translucent material. In this form of key, the coating 12 may be applied to the inside 80 of the aperture 6 within the key in like manner as in that form of key previously described, the two sections 15 and 16 being cemented or otherwise permanently secured in position after the introduction of the 85 coating within the key.

In Figs. 7 and 8 are shown a further slightly modified form of key embodying my invention, also constructed with a body having two or more parts or sections 20 49 and 21, provided with a suitable internally threaded aperture 10, or the like, for the attachment of the stub shaft of the switch, the two sections being cemented or otherwise permanently secured together. In this form 45 of my device the coating 12 is applied to the surface of a preferably substantially conical point 23 formed upon the section 21 and projecting into the cavity 6 within the body of the key. If desired, in this form of key 50 the section 21 need not necessarily be formed of translucent material, although I prefer at least to form the point 23 of material having a light color such as porcelain. It will be evident that the luminous coating 55 upon the point will be visible to the observer from any angle from which the key may be observed when in use.

A slightly modified form of the device is that shown in Fig. 9, which depicts a longitudinal section of one of the members or sections which form the body of the key, such section being taken very slightly back of the meeting face of the member 30. The cavity 6 in this form of the device is preferably formed of substantially conical shape,

substantially one half of the cavity being hollowed from each member, and the luminous coating 12 may be applied to the walls of the cavity, and the members maintained in fixed relation in any desired manner. In 70 this form of key means for attaching the same to a switch or the like, preferably consisting of a suitable threaded aperture 10 are provided, which aperture may be formed directly in the body section or in a separate 75 section 31 maintained in fixed relation to the body section as shown.

The form of key shown in Fig. 10 is quite analogous to that of Fig. 8, the body of the key being formed in two sections 38 and 39, 80 the latter being preferably formed with a somewhat obtuse conical point upon which may be applied the luminous coating 12. The two sections 38 and 39 being secured together in any desired manner, as by a suitable adhesive. The key is provided with a suitable means for attaching to a switch or the like, which may consist of a suitable threaded aperture 10, formed either directly within one section 39 of the key, or else within an 85 extension 42 suitably secured thereto, as shown in Fig. 10, or other equivalent means may be employed. The extension of course need not be of translucent material, nor need the section 39 be constructed thereof 90 in this embodiment of my device.

In Figs. 11 and 12 are shown forms of my invention embodied in pendants suitable for use with pull switches, the pendant shown in Fig. 11 comprising a body formed 100 of two sections 45 and 46, a suitable cavity 48 within the body having a luminous coating 12 applied to its walls, and the pendant being supplied with a light chain 49 or other means for attachment to a switch, the two 105 sections of the pendant being suitably secured in fixed relation after the application of the coating to the interior of the walls. In Fig. 12 the body of the pendant is formed with two sections 50 and 51, a suitable cavity 110 6 being formed between the two sections and the coating 12 being applied to the substantially conical face of the section 50, the two sections being secured together in any desired manner. A cap 52 may be provided as 115 well as means in the form of a light chain 54, or the like, for attaching the pendant to a switch, or the cap may be omitted and the chain attached directly to the body of the 120 pendant.

In Figs. 13 and 14 are shown embodiments of my invention as applied to push buttons for push switches, the form shown in Fig. 13 consisting of a body portion formed in two sections 60 and 61, and having a cavity 6, the walls of which are coated with a luminous coating 12. Suitable means for attaching the push to a switch which may comprise a suitable rod 62, or other 125 equivalent means, are secured to the body of 130

the push button, and the sections thereof are secured together in any suitable way. Fig. 14 shows another form of button also comprising two body sections 65 and 66, together with a shaft 67 for attachment of the button to the switch or the like, a cavity 6 being formed between the faces of the body sections, and a luminous coating 12 being applied to the face of one of the sections, preferably made somewhat conical in form, so as to be readily visible from any position.

It will be evident that in the various forms of my invention which I have illustrated, the luminous surface 12 will be visible from any point in the room in which the key, pendant or push may be used, and from which an observer would look at the key, and the key will always therefore appear as a luminous body from any point from which it may be observed while in use upon a switch. Keys, pushes and pendants constructed in accordance with the principles of my invention may furthermore be used for all purposes and all situations in which the ordinary form of key, push or pendant is now employed.

While I do not desire to limit myself to the use of radiumized zinc sulfid, or other radiumized substance, in a key, push or pendant constructed in accordance with the principles of my invention, as, if I desire, I may make use of any other luminous substance within the cavity in the body of the key, yet I have found that radiumized zinc sulfid, or other radiumized substances, possess a distinct advantage in that they do not have to be exposed from time to time to daylight, or other light, in order to keep them in a luminous condition, and hence, a switch key embodying such a substance will retain these luminous qualities practically indefinitely although it may be located where it is never exposed to light of any sort, as in a dark closet or cellar.

I do not desire furthermore to limit myself to the use of any specific form or type of key, push or pendant, as it will be evident that various changes may be made in the construction and arrangement of the various

details of my device, as well as in the materials from which the same may be constructed, and the manner of forming the keys, without departing from the spirit and scope of my invention as defined in the appended claims.

Having thus described my invention, I claim and desire to protect by Letters Patent of the United States:

1. A luminous switch key comprising a body portion having an interior cavity, a coating of luminous substance in the interior of said cavity, and means for attaching said key to a switch or the like, the luminosity of said coating being visible from any angle. 65

2. A luminous switch key comprising a body portion having a plurality of members and an interior cavity, one or more of said members being formed of translucent material, a coating of luminous material within 70 said cavity, and means for attaching said key to a switch or the like.

3. A luminous switch key comprising a translucent body portion having a plurality of sections, the meeting faces of said sections 75 forming a cavity in the interior of said body portion, means for securing said sections in fixed relation, means for attaching said key to a switch shaft or the like, and a luminous substance coating the walls of said cavity, 80 the luminosity of said substance being observable from any point.

4. A luminous switch key comprising a translucent body portion having a plurality of sections, the meeting faces of said sections 85 being hollowed out to form a cavity in the interior of said body portion, means comprising adhesive material for securing said sections in fixed relation, means for attaching said key to a switch shaft or the like, 90 and a luminous substance coating the walls of said cavity, the luminosity of said substance being observable from any point.

In witness whereof I have hereunto set my hand this 15th day of June, A. D. 1914. 95

MILTON T. ROSENHEIM.
